UNITED STATES PATENT OFFICE.

WILLIAM J. O'LEARY, OF MONTREAL, CANADA.

LOCOMOTIVE TOY AND THE LIKE.

Application filed May 29, 1920, Serial No. 385,218. Renewed November 10, 1923.

To all whom it may concern:

Be it known that I, WILLIAM J. O'LEARY, a subject of the King of England, residing at Montreal, Dominion of Canada, have 5 made a certain new and useful invention in Locomotive Toys and the like, of which the following is a specification.

This invention relates generally to locomotive toys of wheeled type, and more specifically to electrically actuated toys.

It pertains also to certain improvements in electrically energized actuated devices, particularly, but not exclusively, adapted for use in toys, and to electrical connecting 15 and modifying devices designed particularly for use in connection with electrically energized toys.

My invention has as a further object the provision of an electrically operated toy of 20 locomotive type wherein, in addition to the means for accomplishing the locomotive movement, means is provided for sustaining the device on a suitable support against the influence of gravity concomitantly with the 25 operation of the motive elements to accomplish progressive movement of the device.

A further object of my invention is to provide a toy of the kind just specified, wherein the motive element and the sustaining 30 element are energized from the same source.

It is an ancillary object of my invention to provide a mechanical toy of locomotive type wherein the motive elements are so 35 mounted and disposed as to permit their adjustment to vary the course pursued by the toy in its locomotive or progressive movement.

Other and further objects of my invention 40 will be pointed out hereinafter or will be obvious from the specification, claims, and drawings forming a part of this application.

Considered in its general scope, my invention contemplates the provision of a locomotive device which, for the purpose of illustration, may be movable on wheels. Upon the locomotive portion of the device is carried a suitable motive element actuated from a suitable power source and effective to accomplish locomotive or progressive movement 45 of the device. In the event the power elements are energized from an electrical source, the said motive elements may be in the form of a small electrical motor supplied from an external power source, such as the 50 ordinary service line of electrical power,

through the medium of a safety element and electrical connections in the form of wires or other conductors which are freely movable to permit the desired activity of the locomotive portion of the device. These conductors or movable leads are preferably permanently secured to the motive elements, so 60 that others cannot be substituted.

Carried on the locomotive element is a 65 sustaining device whose essential attribute is its capacity for maintaining the locomotive device upon a suitable support against the influence of gravity concurrently with the operation of the motive elements to effect 70 progressive or locomotive movement of the device. If desired, this sustaining element may be electrically energized. In such case it may be desirable to constitute it of a permanent magnet or of an electro-magnet or 75 of a compound permanent and electro-magnet, so that when placed on a support of magnetic material, such as an iron or steel plate or wall, the locomotive device will be sustained thereon against the influence of 80 gravity while the motive elements are effective to move the device along the surface of the support.

For the purpose of disclosing my invention, I have selected as an illustrative embodiment a locomotive device in the form of a military "tank" and have shown an arrangement of motive and sustaining element wherein said parts are energized by 85 electricity.

Inasmuch, however, as the scope of my invention is indicated in the claims and not simply by the illustrative disclosure herein, it is to be understood that the particular 90 disclosures of the locomotive element, motive element and sustaining element are not intended as indicative of the range of embodiments of the invention.

In the accompanying drawings Figure 1 represents a sectional elevation of the device;

Figure 2 a top view with parts broken away;

Figure 3 a diagrammatic illustration of 105 electrical windings and connections which may be employed in the device.

Referring to these illustrations by means of the reference characters applied, let it be understood that the letter C indicates generally the locomotive element of the invention. This includes the body and the parts movable therewith. The body as illustrated is 110

in a conventionalized form of a military tank having side portions 1 connected by a casing portion 2. The casing and side portions form a mounting for the motor frame 4. This is pivoted at 5 to the casing portion, and movably connected at 6 to an arcuate rod 7 mounted at its ends in the side members 1. The rod 7 is curved on a radius from the pivot 5 so that the frame may be swung 10 to various angular positions relative to the longitudinal median line of the body. Mounted on the frame 4 is a motor 8 including the driven shaft 9 which carries the traction wheels 10. The motor is supplied 15 with current from an external source by means of conductors 11 forming a movable connection between the source of supply and the body. This connection is preferably permanently connected to the body, so that 20 others cannot be substituted, it being let in to the casing 2 through an aperture lined with a suitable insulating bushing 12, and its point of connection to the motor concealed and enclosed by the casing 2. Operation 25 of the motor causes rotation of the traction wheels 10, which produces locomotive movement of the body when said wheels are in contact with a suitable support. The direction and course of movement of the 30 body may be varied by changing the angular adjustment of the motor frame on the pivot 5 and rod 7. Trail wheels 14 may be suitably mounted on the body member to maintain it free of the surface on which the device 35 is supported and to afford a rolling support. Suitably mounted on the body is a sustaining element, which in the embodiment shown, is in the form of a magnet 15, the coils 16 of which are adapted to be energized 40 by current conducted on the leads 17 from the conductors 11. In this embodiment of the device the power of the magnet will be effective to sustain the locomotive element 45 on a suitable support S, in the form of a plate of magnetic material such as steel or iron, against the influence of gravity, while the operation of the motive elements will be effective to accomplish progressive or locomotive movement of the body. In this fashion 50 the toy will be enabled to emulate its historical prototype in the surmounting of obstacles and the scaling of steep slopes.

Figure 3 is a diagrammatic illustration of a slightly different form of the present invention wherein the sustaining element comprises a construction in which the axles 13, and the wheels 3 and 10' of a suitable motor are magnetizable material. These axles 13 are surrounded by coils in such manner that 55 when the motor is energized the wheels 3 and 10' are magnetized thereby causing the wheels to be sustained from any magnetizable material such as an iron plate or ceiling, assuming that the energy is sufficient to produce magnetism of such strength as to sus-

tain the weight of the toy. It will be noted by reference to Figure 3 that the adjacent wheels are of opposite polarity. This tends to increase the effectiveness of the magnetic forces. Preferably the wheels 10' are arranged in pairs having a common axis while the wheels 3 are spaced apart from the wheels 10', with the axis of the wheels 3 substantially parallel, preferably, to the axes of the wheels 10' in such manner that the wheels 3 become either pilot or trailer wheels as is common in the art.

By virtue of this arrangement of parts, the coils of the motive element and the sustaining element being supplied with current 80 from a suitable source, the wheels 10', which are mounted on axles 9', will be rotated by the motive element, comprising the coil 8' and operative parts, to give the device progressive movement, while the energization 85 of the coils 16' will magnetize the wheels 10' and 3, so that they are rendered powerfully effective to sustain the device upon a suitable support against the influence of gravity. This magnetic effectiveness of the 90 traction wheels 10' further renders them more effective in propelling the device, because of the increase traction afforded by their magnetic attraction for the support on which they travel.

In this arrangement of the motive element and the sustaining element, it will be observed that the arrangement of the magnetized members provides two lines of support for the device, the supporting members on each line being magnetically effective to secure the desired adhesion to the supporting surface. By virtue of this arrangement the device will be evenly supported, and will not tend to rock away from the supporting surface as in the arrangement wherein the adhesion is on a single line.

Having thus described my invention what I claim is:

1. A locomotive toy comprising a body portion, a drive wheel adapted to support a part of the body portion, an electric motor adapted to operate said drive wheel, a main circuit leading to said motor, a trail wheel adapted to support another part of said body portion, and electromagnetic means connected to said main circuit and mounted in said body portion and connected to the motor circuit in such manner that said electromagnetic means is constantly energized when the motor is energized and is so arranged relatively to the center of gravity of the device as to maintain both the drive wheel and the trail wheel in contact with a surface of material capable of being magnetized when said wheels ordinarily would tend to leave said surface due to gravity whereby said toy may be run upon the under surface of an iron ceiling or the like.

2. A locomotive toy comprising a body portion, a drive wheel adapted to support a part of the body portion, an electric motor adapted to operate said drive wheel, a trail wheel adapted to support another part of said body portion, and electromagnetic means mounted in said body portion and connected to the motor circuit in such manner that said electromagnetic means is energized when the motor is energized and is so arranged relatively to the center of gravity of the device as to maintain both the drive wheel and the trail wheel in contact with a surface of material capable of being magnetized when said wheels ordinarily would tend to leave said surface due to gravity whereby said toy may be run upon the under surface of an iron ceiling or the like.
3. A locomotive toy comprising an elongated body portion, a drive wheel adapted to support the forward part of the body portion, an electric motor adapted to operate said drive wheel, a trail wheel adapted to support the rear part of said body portion, and electromagnetic means mounted in said body portion between said wheels and connected to the motor circuit in such manner that said electromagnetic means is energized when the motor is energized and is so arranged relatively to the center of gravity of the device as to maintain both the drive wheel and the trail wheel in contact with a surface of material capable of being magnetized when said wheels ordinarily would tend to leave said surface due to gravity whereby said toy may be run upon the under surface of an iron ceiling or the like.
4. A locomotive toy comprising a body portion, driving mechanism comprising a motor and a drive wheel mounted in the forward part of said body portion, a trail wheel adjacent the rear part of said body portion an electric circuit leading to said motor, and electromagnetic means connected with said circuit in such manner as to be energized when said motor is energized and to maintain both wheels in contact with a magnetizable material so as to sustain the toy suspended therefrom while the motor is energized.
5. An electromagnetic toy comprising a body portion, an electric motor drive comprising a motor and driving wheels, a frame having the forward end thereof pivoted on the body portion, with the rear end of the said frame being adapted to swing on a suitable guideway to cause the device to travel a predetermined path, and trailer wheels on the rear part of said body portion.
6. An electromagnetic toy comprising a sheet metal body portion, an electric motor drive comprising a motor and driving wheels, a frame having the forward end thereof pivoted on the body portion, a curved guideway carried by the said body portion, the rear end of the said frame being adapted to swing on the said guideway and trailer wheels on the rear part of said body portion.

WILLIAM J. O'LEARY.
